UNITED STATES PATENT OFFICE.

AUGUSTUS FREEBORN BROWN, OF HAVRE DE GRACE, MARYLAND, ASSIGNOR TO GOR-BELL STEEL SPIKE LOCK RAILROAD TIE CORPORATION, OF HAVRE DE GRACE, MARYLAND, A CORPORATION OF MARYLAND.

INSULATING FASTENING MEANS FOR RAILS.

1,142,232.

Specification of Letters Patent. Patented June 8, 1915.

Application filed February 15, 1915. Serial No. 3,275.

To all whom it may concern:

Be it known that I, AUGUSTUS F. BROWN, a citizen of the United States, residing at Havre de Grace, in the county of Harford 5 and State of Maryland, have invented certain new and useful Improvements in Insulating Fastening Means for Rails, of which the following is a specification.

My invention relates to certain new and 10 useful improvements in fastening devices for rails and more particularly to fastening devices for rails which are electrically energized and used in signaling and like systems, and the invention consists of the parts, 15 and the constructions, arrangements and combinations of parts which I will herein-after describe and claim.

A leading object of the present invention is to provide an improved insulated fastening means which is so constructed as to permit the parts thereof to be secured one to the other when positioned and yet will allow the rail to have a movement longitudinally and vertically relatively to the tie.

Another object of the invention resides 25 in providing a fastening means which is simple and durable in construction, inexpensive to manufacture and which will be very efficient and useful in operation.

A further object of the invention resides 30 in providing an improved fastening means which will enable a short circuit to be readily detected by the application of an ammeter used in connection with the rail 35 and a portion of the fastening means.

In the accompanying drawings forming a part of this specification and in which similar reference characters indicate like parts in the several views:—Figure 1 is a longitudinal sectional view of a part of a railway tie showing my improved fastening means applied thereto. Fig. 2 is a perspective view of one of the insulating plates removed. Fig. 3 is a similar view of one of the 40 projector plates removed. Fig. 4 is a perspective view of an insulating plate of slightly modified form. Fig. 5 is a perspective view of a metal plate of modified form.

The present invention is an improvement 45 of the insulating fastening means substantially as shown and described in the prior Patent No. 1,104,660, dated July 21, 1914,

the leading feature of improvement over the said patent being in making the insulating and protecting plates thereof with the open 55 centers and with down-turned flanges at the centers which serve as guides which permit of a slight vertical movement of the rail, when in position, relatively to the tie, but which secure the protecting and insulating 60 plates in position on the tie, while allowing the rail to creep or move longitudinally, as I will hereinafter explain.

In the aforesaid drawing, 10, represents a railway tie of suitable construction. This 65 tie may be of pressed steel or malleable iron, or of other material and for purposes of illustration I have shown the tie as substantially of the character disclosed in my prior Patent No. 1,015,167, dated October 27, 1914, 70 and which tie is provided near each end with a vertical opening, 11, at each side of which is formed a spike receiving recess, 12, into which are driven the spikes, 13, which secure the base flange of the rail, 14, to the 75 tie, but it will be obvious that the present improvements may be used in connection with any form of rail-tie having an opening or a depression underlying the rail and made sufficiently deep to accommodate the novel 80 features of the present invention, which I will hereinafter more fully explain.

In the former Patent No. 1,104,660, before alluded to, there is shown a combined insulating and fastening means which comprises suitable protecting and insulating plates and the leading features of the present invention are identified with these plates. In the former patent, the plates, both protecting and insulating, constitute substantially 85 a rail chair and are of single pieces extending transversely across beneath the base of the rail and having end flanges and projecting tongues which are designed to be bent over and onto the base flange of the 90 rail.

The central portion of the protecting and insulating plates of the prior patent are formed with a depression, whereby one plate is fitted into or nested on the other and the 100 lowermost of the plates fits a slightly depressed portion of the tie, for the purpose of aiding in retaining the chair or plates in place on the tie, a leading object of the

aforesaid patent being, to insulate the rail from the metallic tie and to maintain the insulation in place by depressing the central portions of the metal and insulating plates; 5 also to provide a metallic plate for the purpose of detecting defective insulation.

The depressing of the metallic and insulating plates of the former patent and fitting the depressed portion of one plate into 10 the corresponding socket portion of another plate, provided an interlock between the plates as well as between the lowermost of the plates and the railway tie, which latter had a socket or depressed portion to receive 15 the corresponding portion of the lowermost plate. Extensive investigation and experimenting with the patented construction before alluded to has developed that a metal tie in use should remain stationary in a horizontal direction and have but little up and 20 down movement, while the rails should be permitted to move up and down between the chair and the spike head. Provision should also be made to allow the rail to move longitudinally but without disturbance of the 25 position of the insulating and protecting metal plates.

The depression of the central portions of the metal and insulating plates of the patented construction are not thought to be sufficient in all cases to maintain the plates in 30 position, especially when the rail has an up and down movement, and at the same time a longitudinal or creeping movement, either 35 caused by the trains themselves or by expansion and contraction. This has been largely due to the inability of depressing the fibrous or insulating plates sufficient to overcome the distance the rail will lift the plates 40 in its up and down movement, and at the same time of overcoming any horizontal slipping of the insulating or metal plates, one relatively to the other, or to the tie, when the tie and rail are operating under working 45 conditions.

Experiment has shown me that if the depression in the aforesaid plates was carried through until both the metal and fibrous insulating plates formed below the rail seat 50 lips or projections which extend for a substantial distance below the upper surface of the tie, the possibility of the insulating plate getting out of position by slipping relatively to the metal plates, would be overcome.

To this end and to provide a simple and effective means for insuring the proper position of the metal and insulating plates, one on the other and on the tie, and yet provide for the longitudinal and vertical movement 55 of the rail, I construct the metal plate, 15, and the interposed insulating plate, 16, with open centers and down-turned flanges. This may be done by any well known and approved method; for instance, by slitting the 65 plate and bending down the slit portions to

form the vertical flanges, 17, 17', which flanges may be bent down into engagement with each other and with the flanges of the lowermost or metal plate, 15, in engagement with the opposite walls of the opening 70 formed in the tie directly below the rail seat. When this is done it will be observed that these assembled down-turned flanges are guided by the wall of the aforesaid opening and that the combined metal and insulating 75 plates, which have the projections, 18, corresponding to the aforesaid patented construction and which projections are bent over each other and onto the base flange of the rail, will permit the chair thus formed 80 to rise and fall, as a whole, with the rail and relatively to the stationary tie. At the same time, the aforesaid flanges, 17, 17', by engagement with the walls of the opening in the tie, retain the assembled plates in position 85 on the tie, without possibility of horizontal disengagement of the plates, while permitting the rail to creep or move longitudinally relatively to the tie. Thus, ample provision is made for the longitudinal and 90 vertical movement of the rail, which is found to exist in actual practice, while insuring the proper position of the several plates relative to each other and to the tie.

While I may use single or continuous 95 metal and insulating plates as in the prior construction, but having open centers and down-turned flanges, as described, I prefer, as a matter of economy and to cheapen and facilitate replacement of a damaged or broken plate, to form the metal plate, 15, and the insulating plates, 16, in similar sections each section representing about one-half the width of the combined plate and each section having at its outer side the up-turned 105 flange, 19, and tongue projection, 20, as in the patented construction, before mentioned, and each of said sections having on two opposite edges of its center opening, the down-turned flanges, 17, 17', before mentioned, and which flanges serve as projections which enter for a substantial distance into the tie, and thus form a vertical guide for the chair and a retaining means to prevent the chair from moving horizontally on 110 the tie. This insures the rail insulating parts of my improved construction from getting out of place due to the vertical movement of the rails or to the longitudinal creeping of the same.

It is to be desired that the guide flanges, 17, 17', before mentioned should be at the inner portion of the plates and engage the walls of an opening or recess formed in the tie substantially below the rail seat thereof, 115 because if the plates were provided with a flange or lip on the outside to extend down on the outside of the chair instead of in the center, the construction would be impractical because the movement of the tie against 120 125 130

the road ballast would cause the down-turned flanges soon to be mashed, broken or straightened and to become, therefore, ineffective for maintaining the insulating and protecting plates in place and on the chair.

5 A further advantage in making the metal and insulating plates in sections is that the plates are interchangeable with the 5, 5 $\frac{1}{2}$ and 5 $\frac{3}{4}$ inch rail; if the plates are in one piece it is necessary that plates of different size be employed for each size of rail.

10 While I have mentioned the insulating plate as being of a fibrous nature, I wish it understood that I do not limit my invention to this material, but by the term "insulating" I mean to include any material which will serve to insulate the rail from the various metal portions which are carried on the tie and prevent a short circuiting of the current with which the rail is charged. If a 15 short circuit should occur from any cause, the same may be detected by an ammeter applied to a thin metal plate, 21, interposed between insulating plates, as in the former 20 Patent No. 1,104,660, and which ammeter will indicate the leakage and the operator may then determine approximately at what 25 portion of the line of rails, the short circuit occurs, as disclosed more fully in the aforementioned prior Patent No. 1,104,660.

30 While I have particularly described the elements best adapted to perform the functions set forth, it is obvious that various changes in form, proportion and in the 35 minor details of construction may be resorted to within the scope of the appended claims, without departing from the spirit or sacrificing any of the principles of the invention.

40 Having thus described my invention what I claim as new and desire to secure by Letters Patent is:—

1. In a rail fastening and insulating means, the combination with a rail and a tie 45 having a rail seat and an opening below the same, a chair interposed between said rail and seat having a plate of insulating material on which the rail rests said chair having an opening and said insulating plate having a bottom projection entering said opening and forming therewith a vertical guide which permits the chair to move vertically but prevents a relative horizontal movement between the chair and tie.

55 2. In a rail fastening and insulating means, the combination with a rail and a tie having a rail seat and an opening below the same, of a chair interposed between said rail and seat and including a metallic member and a member of insulating material thereon; said metallic member having an opening aligned with the opening in the tie and said insulating member having a projection on its under side to enter the opening in the metallic member for a substantial

distance and to engage the walls thereof to prevent the horizontal movement of the chair relatively to said tie.

3. In a rail fastening and insulating means, the combination with a rail and a tie 70 having a rail seat and an opening below the same, of a chair interposed between said rail and seat, said chair comprising a metal plate and a plate of insulating material resting thereon, each of said plates having 75 openings adapted to be aligned with each other and with the opening in the tie, and one of said plates having a projection entering the opening of the other plate and the opening in the tie whereby the chair is held against horizontal movement of and relatively to the tie.

4. In a rail fastening and insulating means, the combination with a rail and a tie 80 having a rail seat and an opening below the same, of a metallic tie plate formed of insulating and non-insulating members, said members having bottom flanges projecting below their central portion and for a substantial distance into the opening of the tie, 85 and forming flanges which permit a vertical movement of the chair without removing the flanges from their engagement with the walls of said opening.

5. In a rail fastening and insulating 95 means, the combination with a track rail and a tie therefor, said tie having a rail seat and an opening below the same, of a metallic chair mounted on said tie and an insulating plate applied thereto, means forming interlocking engagement between said chair and insulating plate, said means comprising substantially vertical flanges projecting downwardly from said chair and plate and arranged in parallel close relation whereby the 100 chair and insulating plate are held against horizontal displacement one relatively to the other.

6. In a rail fastening and insulating 110 means, the combination with a track rail and a tie therefor, said tie having a rail seat and an opening below the same, of a metallic chair mounted on said tie and an insulating plate applied thereto, means forming interlocking engagement between said chair and 115 insulating plate, said means comprising vertical flanges projecting downwardly from said chair and plate and arranged in parallel close order whereby the chair and insulating plate are held against horizontal displacement one relatively to the other, said flanges extending for a substantial distance into the opening in the tie and engageable with the walls thereof, whereby the chair and insulating plate and tie are held against movement 120 one relatively to the other.

7. In a rail fastening and insulating 125 means, the combination with a track rail and a tie therefor, said tie having a rail seat and an opening below the same, of a chair com-

- prising an insulating plate receiving the base flanges of the rail thereon, a protecting plate conforming substantially to the insulating plate and receiving the latter thereon, said 45
5 insulating and protecting plates having flanges projecting substantially vertically from their under surfaces and for a substantial distance into said opening and fitting one within the other, and adapted to retain 50
10 the chair and the tie against relative movement. 55
8. In a rail fastening and insulating means, a chair comprising a pair of insulating plates, and metallic spacing means therefor, said plates and spacing means having flanges projecting from the central portion of their under surfaces and one within the other whereby the flanges interlock to prevent relative movement between the plates 60
15 and spacing means. 65
9. In a rail fastening and insulating means, a chair comprising a pair of insulating plates, metallic spacing means therefor and a metallic protecting plate, said insulating plates, spacing means and protecting plate having open centers with flanges extending vertically below the same and one within the other whereby said plate and spacing means are held in interlocked position against relative movement in a horizontal direction. 70
20 10. In a rail fastening and insulating means, the combination with a rail and a tie having a rail seat and an opening below the same, of a chair comprising a pair of insulating plates, metallic spacing means therefor, and a metallic protecting plate for the insulating plate, said insulating plates, spacing means and metallic protecting plate having open centers with flanges extending downwardly from the walls of the openings for a substantial distance into the opening in the tie and forming with the walls of the last-named opening a guide which permits the chair to have a vertical movement relative to the tie. 75

15
20
25
30
35
40
11. In a rail fastening and insulating means, the combination with a rail and a tie having a rail seat, and an opening below the same, of a chair comprising a pair of insulating plates, metallic spacing means therefor, and a metallic protecting plate for the insulating plate, said insulating plates, spacing means and metallic protecting plate having open centers with flanges extending downwardly from the walls of the openings and for a substantial distance into the opening in the tie and forming with the walls of the last-named opening a guide which permits the chair to have a vertical movement relative to the tie, and said flanges adapted to abut the walls of the opening in the tie to thereby restrain the chair against longitudinal movement relatively to the tie. 80
60
65
70
75
12. In a rail fastening and insulating means, a chair comprising an insulating plate and a metallic protecting plate for the same, said insulating plate and protecting plate being formed of sections each section having flanges extending from the under surfaces of its central portion for a substantial distance. 85
13. In a rail fastening, a chair formed of interchangeable sections each of said sections having an opening in its center with flanges depending for a substantial distance from the walls of said opening. 90
